CLAIM

The ornamental design for an automotive wheel, as shown and described.

DESCRIPTION

FIG. 1 is a perspective view of an automotive wheel, showing my new design;

FIG. 2 is another perspective view thereof;

FIG. 3 is a front view thereof;

FIG. 4 is a perspective view without cap of an automotive wheel, showing my new design;

FIG. 5 is another perspective view of FIG. 4;

FIG. 6 is a front view of FIG. 4; and,

FIG. 7 is a side view of the automotive wheel in FIGS 1-6.
